(57) **CLAIM**

The ornamental design for a display fixture, as shown and described.

DESCRIPTION

FIGS. 1 and 2 are perspective views of a display fixture;

FIG. 3 is a front view thereof;

FIG. 4 is a back view thereof;

FIG. 5 is a top view thereof; and,

FIG. 6 is a side view thereof, the opposite side being a mirror image.

The broken lines shown in the drawings are included for purposes of illustrating environment and form no part of the claimed design.
